(57) **CLAIM**

We claim the ornamental design for a lighting device set, as shown and described.

DESCRIPTION

FIG. 1 is a top right perspective view of the diffuser of the lighting device of the design.

FIG. 2 is a right side view of the diffuser of the design. A left side view is a mirror image of the right side view.

FIG. 3 is a front view of the diffuser of the design.

FIG. 4 is a back view of the diffuser of the design.

FIG. 5 is a top view of the diffuser of the design.

FIG. 6 is a bottom view of the diffuser of the design.

FIG. 7 is a top right perspective view of the light stick of the lighting device of the design.

FIG. 8 is a right side view of the light stick of the lighting device of the design. A left side view is a mirror image of the right side view.

FIG. 9 is a front view of the light stick of the design.

FIG. 10 is a back view of the light stick of the design.

FIG. 11 is a top view of the light stick of the design.

FIG. 12 is a bottom view of the light stick of the design.

FIG. 13 is a perspective view of the charger of the lighting device of the design.

FIG. 14 is a right side view of the charger of the design. A left side view is a mirror image of the right side view.

FIG. 15 is a front view of the charger of the design.

FIG. 16 is a back view of the charger of the design.

FIG. 17 is a top view of the charger of the design; and,

FIG. 18 is a bottom view of the charger of the design.

The broken line showing of portions of the lighting device set in FIGS. 4, 10, 16 and 17 forms no part of the claimed design.

1 Claim, 7 Drawing Sheets
